(57) **CLAIM**

The ornamental design for a parking guidance camera, as shown and described.

DESCRIPTION

FIG. 1 is a front perspective view of a parking guidance camera showing our new design;

FIG. 2 is a front view thereof;

FIG. 3 is a rear view thereof;

FIG. 4 is a left side view thereof;

FIG. 5 is a right side view thereof;

(Continued)

FIG. 6 is a top plan view thereof; and,
FIG. 7 is a bottom plan view thereof.
The broken line portions in the drawings form no part of the
claimed design.

1 Claim, 7 Drawing Sheets
